UNITED STATES PATENT OFFICE.

HARRY HUGHES HARRISON, OF LIVERPOOL, ENGLAND, ASSIGNOR TO AUTOMATIC TELEPHONE MANUFACTURING COMPANY LIMITED, OF LIVERPOOL, ENGLAND.

MULTIPLEX TELEGRAPH SYSTEM.

Application filed October 22, 1923, Serial No. 670,113, and in Great Britain October 28, 1922.

The present invention concerns improvements in or relating to telegraph systems and more particularly concerns an arrangement for overcoming the disadvantages of 5 high speed single channel working with Morse code. The chief of these disadvantages is the inability of automatically and selectively routing traffic at points where the line diverges or at intermediate points en 10 route. This flexibility is a great advantage of multiplex systems but up to the present it has not been employed in high capacity systems using the land line Morse code. Owing to the present tendency to extend 15 cables to a group of offices remote from the cable head, automatic routing of traffic has become highly desirable so that retransmission is avoided at the cable station which thereby functions simply as a repeater station and also as the point where cable 20 testing and the adjustment of the duplex balance are undertaken.

Previous attempts at developing a multiplex system using the land line Morse code 25 have been unsuccessful, in that they have tended to give a distorted signal and to increase the time required for the transmission of a message.

The object of the present invention is to 30 provide a multiplex system using the land line Morse code in which the distortion of signals is eliminated and in which the speed of working is substantially equal to that at present attained in high capacity systems 35 with the additional advantage that the messages are sent over different channels instead of over one channel only. Thus in 40 the case of a cable having a one way speed of 90 words per minute, either three channels at 30 words or two channels at 45 words per minute could be arranged for.

According to one feature of the invention, this object is attained in a multiplex system 45 using a code with signal units of unequal length by arranging for the line time to be divided equally among the different channels during periods of time equal to the longest period of which the duration of the individual signal units forming the code 50 are exact multiples, so that each signal unit comprises an integral number of components.

Thus in the case of the land line Morse code the period which is divided among the various channels is the length of a dot, 55 since a dash is as long as three dots.

One way of effecting this is by the provision of two synchronous devices at the transmitting and receiving ends respectively so as to connect up the corresponding transmitting and receiving apparatus of the various channels successively, the receiving apparatus including a polarized relay having no neutral position so that the signal reproduced thereby depends for its duration upon the transmission of current in the opposite direction over the same channel. 60

These features and others not specifically mentioned at this point will be better appreciated from the following description of a system of two channel working taken 70 in conjunction with the accompanying drawings. It will, of course, be understood that the arrangement described is by way of example only and that considerable modifications may be made in the constructional 75 details without departing from the spirit of the invention.

In the drawings, Fig. 1 is a diagram showing how for two channel working with land line Morse code, half of each signal element is suppressed, and Fig. 2 shows how the two sets of signals are combined for transmission over the line. Fig. 3 shows diagrammatically the general arrangements at the sending station for two channel working, while Fig. 4 shows the corresponding arrangements at the receiving end. Fig. 5 shows an alternative driving arrangement for securing synchronism at the sending and receiving ends. 80

Considering Fig. 1 more in detail, time is represented in a horizontal direction and the dotted lines divide the diagram into units such as are used for sending over each channel, *a* represents a Morse signal for the letter L, for sending over the first channel, while *b* represents a second Morse signal (i. e. the letter F), which is to be sent over the second channel. The lines *c* and *d*, from which ordinates above the line represent positive currents and those below the negative currents, represent the actual polarity and duration of the currents sent over the line in respect of each signal. 85

It will be apparent from Fig. 1 that in 105 the case of two channel working, the first channel has the second half of each signal component suppressed, while the second channel similarly has the first half suppressed. For three channel working clearly 110

only one-third of each signal component is actually operative for each channel, and similarly for larger numbers of channels. Fig. 2, which represents the combination of *c* and *d*, Fig. 1, on a single base, shows the resultant current which would flow over the line.

In the sending equipment shown in Fig. 3, T^1 and T^2 are transmitters preferably of the keyboard perforator or similar type, for instance similar to that described in my book "Printing Telegraph Systems and Mechanisms" on pp. 175 and 176. SW^1 and SW^2 are the corresponding star wheels which are rigidly fixed to the shaft carrying the contact brush arm CBA of the rotary distributor. This shaft is driven by a phonic wheel or other suitable synchronous motor which is not shown. The contact brush arm CBA is arranged to sweep over two contact rings, one of which R^1 is solid while the other R^2 is divided up into a number of insulated segments. The length of these segments is such that for two channel working four of them occupy an angle equal to the pitch of the star wheels. Alternate segments are connected together and the two groups are connected through the normally closed contacts of the synchronizing switch SS to the respective transmitter keys.

The solid ring of the distributor is connected to the polarized transmitting relay TR, the armature of which in its operated position connects positive battery to the line L.

The receiving apparatus, Fig. 4 consists of a similar rotary distributor with a contact brush arm CBA^1 . This arm is driven in synchronism with the distributor arm at the transmitting end by means of a phonic wheel PW controlled by an electrical vibrator GR operating on the principle of the Gulstad relay as fully described on pp. 288-290 of my book previously referred to. The upper winding of GR is a correcting winding and is traversed by a momentary current each time the line relay LR reverses, the flow of continuous current being prevented by the condenser c^1 . The speed of vibration may be adjusted by varying the values of the resistances r^1 , r^2 and of the condenser c^2 . By this means the phonic wheel may be regulated by the signals received so that a perfect phase relationship between the transmitting and receiving distributors may be obtained. The synchronizing switch SS provided for adjusting purposes at the transmitting station, is adapted when operated to connect the two groups of segments of the divided ring to positive and negative battery respectively. The transmitting relay TR responds accordingly and connects positive and negative current alternately over the line, whereupon the line relay LR vibrates and sets the Gulstad relay GR in operation. The adjustment of the

auxiliary circuits is then effected in known manner and when the speed of the phonic wheel is correct the phase adjustment is secured either by rotating the divided ring or moving the brushes as is well known.

The rotary distributor at the receiving end also consists of a solid and a segmented ring, alternate segments of the latter being connected together. The groups in this case are connected to polarized storing relays PR^1 , PR^2 , which control receiving apparatus RA^1 , RA^2 corresponding to the two channels. This receiving apparatus may comprise recorders, receiving perforators or the like but is shown in the drawing as a printer of the Creed type and is illustrated in my book as above mentioned on page 353. The polarized relays PR^1 and PR^2 have no neutral position so that when they are operated by a current flowing in one direction they will remain in the operated position until operated upon by a current in the opposite direction when they return to the position from which they were first operated. The armature of the polarized line relay LR is connected to the solid ring of the distributor and this armature is thus connected alternately to PR^1 and PR^2 in exact correspondence with the connections from transmitters T^1 and T^2 to the transmitting relay.

The operation of sending the letters L and F in Fig. 1, will now be followed through in detail. When transmitters T^1 and T^2 , which operate in synchronism, are displaced to send the dot signal which at this point is to be sent over both channels, relay TR is operated in the circuit from battery B, transmitter T^1 , ring R^2 , a segment, contact brush arm CBA, ring R^1 , relay TR, earth. Relay TR thereupon operates and connects positive battery over the line L to line relay LR (Fig. 4). A circuit is thereby completed by the armature of line relay LR from positive battery, ring R^3 , contact brush arm CBA^1 , ring R^4 , a segment, polarized relay PR^1 , earth. The armature of relay PR^1 is therefore operated to control the recording apparatus RA^1 .

When the contact brush arm CBA reaches the adjoining *b* segment, relays TR and LR will be maintained operated but now current is connected over a *b* segment of the receiving rotary distributor to relay PR^2 so that the recording apparatus RA^2 is operated. It should be noted that as relay PR^1 has no neutral position it will remain in the operated position, and thus the recording apparatus will receive a signal of full dot length.

When the next segment is swept over by the contact brush arm, negative current will flow through the transmitting relay TR so that it will reverse its armature and connect negative current over the line. Relays LR and PR^1 are therefore restored to normal

and hence the recording apparatus RA¹ is no longer operated. Similarly during the next half dot when a *b* segment is encountered RA² is restored to normal. The succeeding 5 operation will be readily followed: PR¹ receives three operating impulses and is then reversed and is subsequently operated once and restored; thus a dash and a dot are sent. In the same time a dot and a dash 10 are sent over the second channel so that PR² is operated accordingly.

It will thus be seen that the signals transmitted over the various channels fit into one another for transmission over the line and 15 are then resolved into their components at the receiving end. This method clearly permits the most efficient utilization of line time while securing the advantages of multiplex working with the land line Morse code.

20 In Fig. 5 is shown a modification of the transmitting apparatus which does away with the necessity for having the star wheels on the same shaft as the contact brush arm of the rotary distributor. According to this 25 arrangement, the distributor has four rings R⁵, R⁶, R⁷ and R⁸, the outer pair of which R⁵ and R⁶ serve the same purpose as the rings R¹ and R² in Fig. 3. R⁸ is solid and 30 is connected to earth, while R⁷ is divided into the same number of segments as R⁵, alternate segments being left blank and the remainder being connected to a single wire. This wire leads to stepping magnets SM¹, 35 SM² which are arranged to operate ratchet wheels RW¹, RW² to which the star wheels are rigidly connected. These ratchet wheels have twice as many teeth as the star wheels and thus are driven at the same rate as the 40 rotary distributor. Obviously now, the transmitters and star wheels may be controlled from the transmitting distributor, over a single wire.

What I claim is:

45 1. A multiplex telegraph system comprising a plurality of automatic transmitting devices, circuit closing means controlled by said devices and adapted to be operated for unequal periods of time to transmit different signal elements, a transmitting relay, a distributor, inter-connecting arrangements between said transmitting devices and said distributor for securing the connection of said devices successively to said relay during 50 periods of time equal to the longest period of which all the signal elements are exact multiples; a telegraph line connected at one end to contacts of said transmitting relay, a line relay connected to the other end of said line, a plurality of receiving devices 55 corresponding in number to the number of transmitting devices and a second distributor controlled so as to have a movement corresponding to that of said first distributor to enable said line relay to control said receiving devices in accordance with the sig-

nals transmitted from the corresponding transmitting devices.

2. A multiplex telegraph system employing the land line Morse code in which the signal element for the dash signal is three 70 times the length of the signal element for the dot signal comprising a plurality of automatic transmitting devices, circuit closing means controlled by said devices and adapted to be operated for unequal periods 75 of time to transmit either dots or dashes, a transmitting relay, a distributor, interconnecting arrangements between said transmitting devices and said distributor for securing the connection of said devices successively to said relay during periods of 80 time equal to the length of the dot signal, a telegraph line connected at one end to contacts of said transmitting relay, a line relay connected to the other end of said line, a plurality of receiving devices corresponding in number to the number of transmitting devices and a second distributor controlled so as to have a movement corresponding to that of 85 said first distributor to enable said line relay to control said receiving devices in accordance with the signals transmitted from the corresponding transmitting devices.

3. A multiplex telegraph system comprising a plurality of automatic transmitting devices, circuit closing means controlled by said devices and adapted to be operated for unequal periods of time to transmit different signal elements, a telegraph line, a distributor at the transmitting end of said line, 95 inter-connecting arrangements between said transmitting devices and said distributor for securing the division of the line time equally 100 between said transmitting devices during periods of time equal to the longest period 105 of which all the signal elements are exact multiples, a plurality of receiving devices corresponding in number to the number of transmitting devices, a line relay connected to the receiving end of said line, and a second distributor located at the receiving end 110 of said line for dividing the line time equally between said receiving devices by connecting contacts of said line relay to said receiving devices in correspondence with the connection of said transmitting devices to said line, said receiving devices being adapted to take up a new position only in response to a modification of current transmitted to 115 the line by the corresponding transmitting device.

4. A multiplex telegraph system comprising a plurality of automatic transmitting devices, circuit closing means controlled by said devices and adapted to be operated for unequal periods of time to transmit different signal elements, a transmitting relay, a distributor, inter-connecting arrangements between said transmitting devices and said distributor for securing the connection of 125 130

- 5 said devices successively to said relay during periods of time equal to the longest period of which all the signal elements are exact multiples, a telegraph line connected at one end to contacts of said transmitting relay, a line relay connected to the other end of said line, a plurality of two-position polarized relays corresponding in number to the number of said transmitting devices and adapted 10 to remain in either position until moved to the opposite position by a reversal of current in their windings and a second distributor controlled so as to have a movement corresponding to that of said first distributor 15 to enable said line relay to control said polarized relays to be operated to one position in accordance with the operation of said circuit closing means.
5. In combination, for use in a multiplex 20 telegraph system, a plurality of automatic transmitting devices, circuit closing means controlled by said devices and adapted to be operated for unequal periods of time to transmit different signal elements, a transmitting relay, a distributor, inter-connecting 25 arrangements between said transmitting devices and said distributor for securing the connection of said devices successively to

said relay during periods of time equal to the longest period of which all the signal elements are exact multiples, and a cable connected to contacts of said transmitting relay.

6. In combination for use in a multiplex telegraph system employing a code with signal elements of unequal length, a cable, a line relay adapted to be operated over said cable, contacts controlled by said line relay, a plurality of receiving devices adapted to take up a new position only in response to a 40 change of position of said line relay contacts when said contacts are connected thereto, a distributor, circuit connections between said distributor and said receiving devices, driving means for said distributor and inter-connecting arrangements between said driving means and said line relay contacts for controlling the speed of said distributor so that said line relay contacts are connected 45 successively to said receiving devices during periods of time equal to the longest period of which all the signal units are exact multiples.

Signed by me at Liverpool, England, this 5th day of October, 1923.

HARRY HUGHES HARRISON.
